PIN PAPER MAGAZINE

Filed Jan. 25, 1928

By

Attorneys.

UNITED STATES PATENT OFFICE

WESLEY E. WINN, OF SAN FRANCISCO, CALIFORNIA

PIN-PAPER MAGAZINE

Application filed January 25, 1928. Serial No. 249,484.

My invention relates to improvements in pin-paper magazines, and it consists in the combinations, constructions, and arrangements hereinafter described and claimed.

An object of my invention is to provide a pin-paper magazine which houses a paper of pins and which has novel means for supporting and exposing one row of pins at a time. This means permits the withdrawal of any number of pins from the exposed row as desired.

A further object of my invention is to provide a device of the type described that has a spring actuated door normally held in closed position. The spring is strong enough for causing the door to clamp the paper between it and the magazine proper with sufficient force to hold the paper in place while permitting the pins to be removed.

Other objects and advantages will appear in the following specification, and the novel features of my invention will be particularly pointed out in what I hereinafter claim.

My invention is illustrated in the accompanying drawing forming a part of this application, in which:

Figure 1 is a front elevation of the device partially broken away for showing the paper of pins;

Figure 2 is a transverse section of the magazine;

Figure 3 is an enlarged sectional view of a portion of the device shown in Figure 2;

Figures 4 and 5 are a plan and a side view, respectively, of a spring hook used in the device; and

Figure 6 is a perspective enlarged detail sectional view of a portion of the device.

In carrying out my invention I provide a magazine indicated generally at 1. The magazine takes the shape of a box having end walls 2, a rear wall 3, a top wall 4, and a bottom wall 5. The magazine has an open front that is normally closed by a door 6.

This door is removably secured to the magazine by a leaf spring 7, and this spring is also used for yieldingly holding the door in closed position. In Figure 2 I show the bottom of the door as being provided with a compartment 8, formed by a bottom flange 9 of the

door, and inwardly extending end portions 10 of the door. When the door is in vertical position, the flange 9 extends at an angle with respect to the floor 5. The door fulcrums about its bottom edge 11 as a pivot.

It should be noted that this pivot slides over the bottom of floor 5 and is disposed to the left in Figure 2, when the door is in full open position, as indicated by the dotted lines. The leaf spring 7 is substantially of the same area as the bottom 5 and it is secured to the bottom by means of bolts 12. The front edge of the spring is soldered, as shown at 13, and is removably received in the pocket of recess 8. The spring is strong enough to swing the door from a partially open position into closed position. When the door is in full open position, as shown by the dotted lines, the spring will not return it into closed position.

The magazine houses a paper 14 carrying common pins 15. This paper of pins is the usual article that is purchasable at any dry-goods store, etc. The device is designed for exposing one row of pins at a time and for holding these pins in a position where they may be readily removed from the paper without in any way effecting the other pins, or in removing the paper from the magazine. Reference to Figure 3 clearly shows how the exposed row of pins is supported. A shoulder 16 is provided on the inner side of the door 6, and is formed by a strip of metal 17, see Figure 6. This strip is held in place by inwardly bent lugs 18, and also by solder that secures the flange 19 to the door, and also the edge 20.

The points of the pins rest upon the shoulder 16, while the heads project above the top of the magazine. The paper of pins is clamped between a flange 21, formed from the front portion of the upper wall 4, and the upper part of the door 6. The row of pins to be exposed are initially secured to the door 6 by springs 22, while the door is in full open position. The springs 22 aided by the spring 7 hold the paper 14 in place, and permit any number of pins 15 to be removed.

In Figures 4, 5, and 6 is shown the novel type of spring 22 employed. There are two

of these, one being disposed at each end of the door. The spring is U-shaped, and has outwardly projecting ends 23 that are rotatably received in sleeves 24. The sleeves have notches 25 for receiving a portion of the legs 26 and these notches are disposed so as to hold the spring in operative position.

From the foregoing description of the various parts of the device, the operation there-
10 of may be readily understood.

The door 6 is swung into full open position, and the paper of pins is inserted into the magazine. One of the ends of the paper is clamped to the door by means of the springs
15 22. The portion of the paper so clamped disposes the row of pins carried thereby upon the shoulder 16, the door is now swung into closed position and the pins will project above the magazine as shown in Figures 1 and 3.
20 Any number of pins may now be removed from the row. The same operation is repeated when a new row of pins is needed. The magazine entirely conceals the unused portion of the paper.

25 Although I have shown and described one embodiment of my invention, it is to be understood that the same is susceptible of various changes and I reserve the right to employ such changes as may come within the scope of
30 the invention as claimed.

I claim:

1. A device of the type described comprising a magazine having an open front, and being made large enough for receiving a paper of pins, a spring actuated door normally held in closed position by a spring, spring actuated clips carried by said door for securing the paper of pins thereto, and a shoulder for supporting the exposed row of pins,
35 and for holding them in a position where the heads will project above the top of the magazine.

2. In a device of the type described, a magazine having an upper wall formed with a flange extending across one edge, a door swingable into a position facing the flange, means carried by said door for securing a paper of pins thereto, and a spring for yield-
45 ingly holding said door in closed position
50 whereby said door and flange will clamp a paper of pins therebetween.

3. A pin-holding device comprising a magazine for receiving a pin-supporting strip on which the pins are arranged in rows, a shoulder carried by the device for supporting the ends of a row of pins, said magazine having an opening, said shoulder holding the pins in a position where the heads of all
55 of the pins in the row will project through
60 the magazine opening, said magazine shield-
ing the ends of the pins.

4. A pin-holding device comprising a magazine having a pair of members for firmly clamping a row of pins therebetween, the
65 heads of the pins projecting from the mem-

bers, and a shoulder carried by one of the members for supporting the pointed ends of all of the pins in the row.

5. A device of the type described comprising a magazine having an open front, and being made large enough for receiving a paper of pins, a door, spring actuated clips carried by said door for securing the paper of pins thereto, and a shoulder for supporting the exposed row of pins, and for holding them in a position where the heads will project above the top of the magazine.

6. In a device of the type described, a pin-paper magazine having an opening and an abutment disposed at one edge of the opening, a door swingable against the abutment for clamping a paper of pins therebetween, and a support for the pointed ends of the pins, said support being arranged for causing the pin heads to project beyond the magazine.

7. A pin-paper magazine comprising a container for a paper of pins, said container having an opening, a door for the opening, said door when closed being designed to clamp a row of pins between the door and container for causing the heads of the pins to project beyond the container, and means for supporting the pointed ends of the exposed row of pins and for preventing a movement of these pins into the container when they are grasped.
